RAZOR OR THE LIKE

William R. Pomper, Highland Park, Ill.
(140 S. Dearborn St., Chicago, Ill.)

Filed Sept. 13, 1965, Ser. No. 86,969

Term of patent 14 years

(Cl. D22—3)

FIG. 1 is a front elevation of a razor illustrating my new design;

FIG. 2 is a rear elevation of the razor of FIG. 1;

FIG. 3 is a top plan view of the razor of FIG. 1;

FIG. 4 is a side view of a portion of the razor of FIG. 1; and

FIG. 5 is a side view of the other side of the portion of the razor shown in FIG. 4.

I claim:

The ornamental design for a razor or the like, substantially as shown.
